OTHER PUBLICATIONS

National Business Furniture, p. 119, chair at bottom right.

Primary Examiner—Mimosa De(74) *Attorney, Agent, or Firm*—Workman Nydegger(57) **CLAIM**

The ornamental design for a chair, as shown and described.

DESCRIPTION

FIG. 1 is a front perspective view of a chair;
 FIG. 2 is a rear perspective view of the chair;
 FIG. 3 is a front view of the chair;
 FIG. 4 is a back view of the chair;
 FIG. 5 is a right side view of the chair, with the left side view
 being a mirror image thereof;
 FIG. 6 is a top view of the chair; and,
 FIG. 7 is a bottom view of the chair.

The broken lines shown in the figures are for illustrative
 purposes only and form no part of the claimed design.
